US0D1083525S

(12) **United States Design Patent** (10) **Patent No.:** **US D1,083,525 S**
(45) **Date of Patent:** **** Jul. 15, 2025**

(54) **KNIFE**

(71) Applicant: **Sabert Corporation**, Sayreville, NJ (US)

(72) Inventor: **Yohanan Siskindovich**, Florham Park, NJ (US)

(73) Assignee: **Sabert Corporation**, Sayreville, NJ (US)

(**) Term: **15 Years**

(21) Appl. No.: **29/905,281**

(22) Filed: **Oct. 18, 2023**

(51) **LOC (15) Cl.** **07-03**

(52) **U.S. Cl.**

USPC **D7/650**

(58) **Field of Classification Search**

(57) **CLAIM**

The ornamental design for a knife as shown and described.

DESCRIPTION

FIG. 1 is top right perspective view of a knife according to my design;

FIG. 2 is a top left perspective view thereof;

FIG. 3 is a top plan view thereof;

FIG. 4 is a bottom plan view thereof;

FIG. 5 is a right side view thereof;

FIG. 6 is a left side view thereof;

FIG. 7 is a front view thereof;

FIG. 8 is a back view thereof;

FIG. 9 is a cross section along the line 9-9 of FIG. 3; and,

FIG. 10 is a cross section along the line 10-10 of FIG. 3.

1 Claim, 5 Drawing Sheets
